(57) **CLAIM**

The ornamental design for a vehicle search lamp, as shown and described.

DESCRIPTION

FIG. 1 is a perspective view of a vehicle search lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left side perspective view thereof; and,

FIG. 9 is a perspective view thereof, showing the vehicle search lamp without the lampshade for clarity of illustration. The shading and cross-hatching are not features of the design but are utilized to illustrate the surface contours of the vehicle search lamp design in the drawings.

The broken lines in the drawings depict portions of the vehicle search lamp that form no part of the claimed design.
